UNITED STATES PATENT OFFICE.

RUTHFORD C. CONSTANTINE, OF CINCINNATI, OHIO, ASSIGNOR TO THE SEINSHEIMER PAPER COMPANY, INC., OF CINCINNATI, OHIO.

MERCHANDISE-WRAPPER.

1,068,859.

Specification of Letters Patent.

Patented July 29, 1913.

Application filed July 21, 1911. Serial No. 639,847.

To all whom it may concern:

Be it known that I, RUTHFORD C. CONSTANTINE, a citizen of the United States, residing at Cincinnati, in the county of Hamilton and State of Ohio, have invented certain new and useful Improvements in Merchandise-Wrappers, of which the following is a specification.

My invention relates to merchandise wrappers, and has for its object the provision of a new and improved wrapper intended particularly to wrap laundered articles, such as shirts and the like.

It embraces a stiff back sheet for lending support to the laundered article and a thin transparent front sheet through which the pattern on the laundered article can be seen, and securing means so arranged that the article may be firmly inclosed irrespective of its bulk.

The invention will be readily understood from the following description and claim, and from the drawing, in which latter:

Figure 1 is a perspective view of my improved device, in partly open relation. Fig. 2 is a cross-section of the same on a line corresponding to the line 2—2 of Fig. 3, showing the same in flat relation, with the flap turned under. Fig. 3 is a rear elevation of the same, showing a shirt wrapped thereby, and showing the closure thereof in one of its closing positions in full lines and in another of its closing positions in dotted lines,—and, Fig. 4 is a cross-section of my improved device taken on the line 2—2 of Fig. 3, showing the same in closed position for a comparatively bulky article in full lines and in closed position for a less bulky article in dotted lines.

11 represents a back sheet of such rigidity or stiffness as to form a support for the article being wrapped. I shall hereinafter refer to this sheet as the stiff back sheet. It may be of straw-board or other material suitable for the purpose. It aids in lending rigidity to the package. It is preferably of greater length than width and is desirably of a shape to correspond to the shape of the folded laundered article.

12 is a thin transparent sheet arranged to be received across the face of the article being wrapped and forms a covering protecting sheet for the article. This thin transparent sheet is of a greater width than the back sheet, one edge 13, of the thin trans-

parent sheet being secured lengthwise of one of the lengthwise edges 14 of the back sheet, the edge 13 being pasted as shown at 15 to the rear face of the edge 14, the thin transparent sheet passing thence toward the front face of the back sheet and across the same, and thence again to the rear of the back sheet for forming a flap 16, preferably with a score 17, as shown in Figs. 1 and 2, coincident with the other edge 18 of the back sheet when the wrapper has no article therein so that the same may be conveniently stacked, handled and shipped.

The outer corners of the flap recede as shown at 19 and a plurality of securing strips shown at 20, are secured to the free end of the thin transparent sheet adjacent to the inner ends of the receding portions of said corners. One of the sides of each of these strips is provided with a coating 21 of paste by which one of the ends of each of the strips is pasted to the lateral end of the thin transparent sheet, the other end of each of said strips projecting laterally from the thin transparent sheet, the inner faces of 80 these laterally projecting portions of these strips being provided with said coating of paste in dry state.

The thin transparent sheet is passed across the article being wrapped and the flap passed to the rear face of the back sheet, where it is pulled at the strips for drawing the thin transparent sheet firmly across the article being wrapped, the paste-coated projecting ends of the strips being wet and pressed against the rear face of the back sheet at any lateral portion of the latter necessary to make a firmly wrapped package. If a bulky article is being wrapped, the flap and strip will not extend as far across the rear face of the back sheet as when a less bulky article is being wrapped, as shown in Figs. 3 and 4.

The strains upon the outer or normally free end of the thin transparent sheet are 100 in diagonal lines between the respective spaced-apart attaching strips and the respective upper and lower edges of the thin transparent sheet outside of, but adjacent to the score 17, the exact point of intersection of said lines of stress with said upper and lower edges depending upon the bulk of the article being wrapped. In order to avoid the presence of loose portions of said flap at said corners, I remove said loose 110

portions and form receding corners 19 between said upper and lower edges of said thin transparent sheet and the spaced-apart flap portions thereon. In this manner I 5 provide a firm package, the edges of which are maintained taut throughout and avoid the danger of having said edges torn or damaged by the rubbing of one wrapped package upon another.

10 Having thus fully described my invention, what I claim as new and desire to secure by Letters Patent, is:

A merchandise wrapper for laundered shirts, and the like, consisting of a relatively 15 stiff back sheet having parallel lateral edges and a relatively thin front sheet of the same length as the back but of a width greater than the said back sheet, the said front sheet having parallel lateral edges and 20 having one of its lateral edge portions permanently secured to the rear face of the back sheet at one lateral edge thereof, the front sheet at its side opposite its said attached side having its corners cut diagonally, and 25 tabs permanently attached to the outer face of the front sheet at the last mentioned side thereof and projecting beyond the corre-

sponding lateral edge, the tabs being located one near the top of the front sheet and the other near the bottom thereof and spaced 30 apart nearly the entire length of the sheet and substantially at the points of intersection of the diagonal corners of the sheet with the last mentioned lateral edge thereof, the front sheet being adapted to be stretched 35 over a laundered article disposed against the front face of the back sheet and over the lateral edge of the back sheet opposite that edge at which the front sheet is permanently secured, the surplus width of the front sheet 40 being arranged to lie against the rear face of the back sheet, and the tabs being provided each with adhesive whereby the tabs may be secured to the rear face of the back sheet at indeterminate points considerably 45 spaced above and below the transverse median line of the said back sheet.

In testimony whereof, I have signed my name hereto in the presence of two subscribing witnesses.

RUTHFORD C. CONSTANTINE.
